Primary Examiner — Austin Murphy(74) *Attorney, Agent, or Firm* — Richard A. Johnson; Borden Ladner Gervais LLP(57) **CLAIM**

The ornamental design for a modular heads-up display system, as shown and described.

DESCRIPTION

FIG. 1 is a perspective view of the modular heads-up display system showing the design; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an exploded view thereof; and,

FIG. 9 is a perspective view showing the modular heads-up display system coupled to a pair of goggles.

The goggles and strap clip are shown in broken lines for illustrative purposes only and form no part of the claimed design.

1 Claim, 5 Drawing Sheets(56)
